US00D759724S

(12) **United States Design Patent**
Kim et al.

(10) **Patent No.:** **US D759,724 S**
(45) **Date of Patent:** **** Jun. 21, 2016**

(54) **DISPLAY SCREEN OR PORTION THEREOF
WITH GRAPHICAL USER INTERFACE**

(71) Applicant: **Samsung Electronics Co., Ltd.,**
Suwon-si, Gyeonggi-do (KR)

(72) Inventors: **Ji-Hoon Kim, Seoul (KR); Jong-Hyun
Shin, Seoul (KR)**

(73) Assignee: **SAMSUNG ELECTRONICS CO.,
LTD. (KR)**

(**) Term: **14 Years**

(21) Appl. No.: **29/510,159**

(22) Filed: **Nov. 25, 2014**

(30) **Foreign Application Priority Data**

(57) **CLAIM**

We claim, the ornamental design for a display screen or portion thereof with graphical user interface, as shown and described.

DESCRIPTION

FIG. 1 is a front view of a display screen or portion thereof with graphical user interface, showing our new design, the icon is shown separately for clarity of illustration, on an enlarged scale; and,

FIG. 2 is another front view thereof.

The broken lines depicting a display screen or portion thereof are for environmental purposes only and form no part of the claimed design. The broken lines depict portions of the article and graphical user interface and form no part of the claimed design.

1 Claim, 2 Drawing Sheets
